UNITED STATES PATENT OFFICE

2,431,273

ELECTRON DISCHARGE DEVICE EMPLOYING A CAVITY RESONATOR

Leon S. Nergaard, Princeton, N. J., assignor to
Radio Corporation of America, a corporation of
Delaware

Application April 17, 1944, Serial No. 531,312

19 Claims. (Cl. 315—39)

1

My invention relates to apparatus useful at ultra-high frequencies and more particularly to electron discharge devices and associated circuits of the cavity resonator type.

An object of my invention is to provide an electron discharge device and associated circuit particularly suitable for high frequency operation and capable of delivering large amounts of power.

Another object of my invention is to provide an electron discharge device which can deliver large amounts of power at high frequencies, but which is nevertheless small and compact, has few parts, and lends itself readily to manufacture.

A more specific object of my invention is to provide an electron discharge device in which the electrodes although closely spaced are firmly and rigidly supported with respect to each other.

A further object of my invention is to provide an electron discharge device having electrode leads and supports which will merge into high frequency circuits of the cavity resonator type so that the internal reactances may be coupled smoothly to the external reactances which complete the circuit and thus reduce radio frequency losses and spurious modes of oscillation to a minimum.

Another specific object of my invention is to provide a cathode which will promote heater power economy.

A further object of my invention is to provide a cavity resonator circuit in which the circuit has large dimensions while permitting operation at very high frequencies.

Another object of my invention is to provide an electron discharge device and associated circuits comprising cavity resonators which provide a novel method of introducing biasing voltages on the electrodes enclosed within the cavity resonators.

A further object of my invention is to provide improved means for connecting the terminals of an electron discharge device to a cavity resonator circuit.

Another object of my invention is to provide push-pull circuits for an electron discharge device made according to my invention and using a novel type of coaxial line resonator.

A still further object of my invention is to provide an electron discharge device of the type described above utilizing a novel cavity resonator circuit associated therewith and novel means for cooling the device during operation.

The novel features which I believe to be characteristic of my invention are set forth with particularity in the appended claims, but the inven-

2

tion itself will best be understood by reference to the following description taken in connection with the accompanying drawing in which Figure 1 is a longitudinal section of an electron discharge device and associated circuit made according to my invention; Figure 2 is a longitudinal section of an electron discharge device made according to my invention and of the type utilized in Figure 1; Figure 3 is a longitudinal section of a modification of the electron discharge device and associated circuit shown in Figure 1, and Figure 4 is a longitudinal section of the electron discharge device shown in Figure 3.

In accordance with my invention I provide an electron discharge device having an indirectly heated cathode 10 of cup-shape surrounded by a cup-shaped grid 11, both nested within anode 12 provided with longitudinally extending heat radiating fins 13. The anode provides part of the envelope and is provided with a collar 14 of U-shaped transverse section. The outer rim of the collar 14 is sealed to the insulating collar 15. The header for the tube envelope includes a disc member 19 welded at 17 to a collar 16 sealed to the other end of insulating collar 15. The disc or header 19 is provided with collar 18 sealed by means of a transverse flat press 20 through which the leads 49 extend. These leads support the conducting collar 21 on which the cathode is mounted. The grid is supported by means of cone-shaped collar 22 mounted on the disc 19. This device will be described in more detail below in connection with Figure 2.

An input circuit of the coaxial line type providing a cavity resonator is coupled to the device described and comprises an inner tubular member 25 capacity coupled to the cathode leads. A collar 28 provides the cathode lead socket and is capacity coupled to the tubular member 25 through the insulating collar 29, preferably of mica. The outer tubular member 26 is connected to the inner tubular member by closure member 27. The outer tubular member is provided with a plurality of spring fingers 32 engaging the outer periphery of the header member 19, upon which the grid is supported and to which it is electrically connected. A shorting member 31 tunes the circuit. Thus the cavity resonator is coupled between the grid and cathode of the electron discharge device.

The output circuit is a novel push-pull cavity resonator type and comprises an inner tubular member 35 which receives within one end the radiating fins 13 and the anode 12 of the electron discharge device and the outer tubular mem-

ber 38 surrounding the inner tubular member. This circuit can operate in a half wave mode or a multiple thereof depending upon the adjustment of the cathode circuit.

At the other end of the output cavity resonator is a second electron discharge device of the type first described. A coaxial input circuit 26' identical with that connected to the electron discharge device first described is coupled to the cathode and grid of this second electron discharge device and the member 35 receives within it the anode 12' and radiating fins 13'.

The outer tubular member 38 of the cavity resonator has an aperture 37 through which tubular member 36 extends, this member being connected electrically to the inner tubular member 35 of the cavity resonator. This tubular member 36 serves as a lead for the anode voltage and also as a duct for directing cooling air into the inner member 35 and out into the outer member past the longitudinally extending cooling fins 13 and 13' over the insulating collar members 15 and 15', and back out through the aperture 37. The output may be taken by means of a coaxial line comprising inner conductor 35' and outer conductor 38'. Feedback may be of any type but is shown as a coaxial coupling line coupled between the input and output circuits and including an inner conductor 25' and an outer conductor 26''.

The electron discharge device utilized in my high frequency apparatus is shown in greater detail in Figure 2. The cup-shaped indirectly heated cathode 19 is provided with heater 10', one end of which is connected to the cathode and the other end of which is connected by means of lead 10'' to a lead wire 48' sealed through the press 20. The lead-in conductors 48 mounted in a circle are enclosed within and connected to a supporting cathode collar 21, the cathode proper being supported by means of ribbon-like conducting members 47 to reduce heat conduction between the cathode and collar 21. The grid 11 is provided with a top cap 11' having a plurality of apertures 11'' for reducing heat flow from the center of the cap to the grid wires. The top cap has a cathode-grid aligning hole in the center through which the conductor 49 from the cathode extends and is supported from the top cap by means of the insulating tubular member 50. The grid 11 is firmly and rigidly supported by means of the cone-shaped member 22 sealed to the header member 19, which may be a fernico ring.

The cathode may be of silicon nickel ribbon coated on the surface with the usual carbonates. The lower end of the cathode thimble is closed by heat shield 46. The heater 10' may be of tungsten wire and cylinder 21 may be nickel and the supporting tabs 47 may be of copper plated kovar, the tabs serving to heat insulate the cathode as well as provide electrical contact. There is no contact between the sleeve 21 and the heater lead 48' to which the cathode heater lead 10'' is connected. The getter pellet 51 may be connected between the lead 49 and the cathode cylinder 21 to provide a flashing circuit.

As pointed out above, the grid and cathode are enclosed within the anode 12 provided with the vertical or longitudinally extending heat radiating fins 13, the anode being a copper thimble to which may be silver soldered the kovar sealing collar or ring 14 of transverse U-section. The envelope is completed by means of the insulating collar 15, preferably of glass sealed to the outer lip of collar 14 and the collar 16, which is pro-

vided with a flange 16' welded at 17 to the disc 19 of the header. With the arrangement shown the cathode and grid can be first mounted on the header member, and the anode assembly 5 sealed thereover to disc 19 by welding. This would avoid the necessity employed in one method of assembly first requiring forming the envelope, cracking the collar 15 and re-sealing the same after mounting the cathode and grid upon the header. In the arrangement shown there is no danger of cracking of the button stem, due to uneven heating which would occur in re-sealing a cracked envelope collar 15.

The apparatus described can function at very high frequencies, of the order of 1200 megacycles or higher and deliver large amounts of power although occupying small space, which is of importance in certain applications, and permits adequate cooling. The tube and circuit merge into each other to provide an efficient high frequency apparatus. The cavity resonator circuits, despite the high frequency at which the apparatus is designed to operate, are of reasonable size providing desirable external reactances which can be tuned.

In Figure 3 I show a modification of an electron discharge device and associated circuit made according to my invention. This is a single tube circuit utilizing a tube much like that shown in Figure 2. The grid-anode circuit again of the coaxial line type consists of the inner tubular member 25'', the outer tubular member 26'', closure member 27' coupled between the cathode 10 and grid 11, and the shorting tuning ring 31'.

The output circuit now comprises the inner conductor 46' having a slidable collar 47' for determining the length of the inner tubular member. The member 46' is slipped over and engages the radiating fins 13 of the electron discharge device. The outer tubular member 48'' is provided with an extension 50' having a further extension 61. The extension 50' is provided with an aperture closed by means of insulating conducting member 52 through which the high voltage anode lead 49' extends. The lead 49' contacts the inner tubular member 46' at a voltage nodal point for supplying the anode voltage. A transverse insulating member 53 is positioned between the inner and outer tubular members to direct the flow of cooling air which is admitted at extension 61 into proper channels. The upper end of the member 48'' is provided with an aperture surrounded by collar 54 through which the inner conductor 55 of the coaxial line, comprising conductors 55 and 55', extends, the aperture being sealed by insulating member 56, and the lower end of the coupling member 55 extending within the collar 47' for coupling the coaxial line to the output circuit. The cooling medium may be directed through the extension 61 along the lines indicated by the arrows for the flow of the cooling medium, past springs 32' into the input circuit, past tuning ring 31' and rods 31''. This circuit may operate in a half wave mode or a multiple thereof.

In Figure 4, showing details, is a modification of the electron discharge device shown in Figure 2. Like members designate like parts. The cathode heater 57 is slightly different and the header member comprises ring 16' and is provided with oppositely directed flanges 58 and 59, the press being supported within and sealed to the flange 58, the flange 59 being sealed to the insulating collar 15.

While I have indicated the preferred embodiment

ments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having an anode, a grid and a cathode, resonator means coupled between the cathode and grid, and a cavity resonator coupled between said grid and anode and having an inner conductor coupled to said anode and comprising an elongated member engaging and extending from said anode, and a hollow member surrounding the elongated member but out of electrical contact therewith but enclosing said elongated member, said hollow member having an aperture therein and means extending through said aperture and connected to said inner conductor for applying a voltage to said inner conductor.

2. An electron discharge device having an envelope closed at one end by an anode forming part of the envelope for said electron discharge device, a grid within said envelope having conducting means extending radially through said envelope and supporting said grid and a cathode within said envelope having conducting means extending through said envelope, a cavity resonator coupled between the cathode and grid conducting means and a cavity resonator coupled between said grid and anode and having an inner conductor coupled to said anode and comprising an elongated member having one end engaging and extending from said anode and a hollow member surrounding the elongated member but out of electrical contact therewith and enclosing said elongated member, said hollow member having an aperture oppositely disposed to the free end of the elongated member and electrically conducting means extending through said aperture and coupled to said elongated member.

3. An electron discharge device having an anode, a grid having conducting means extending therefrom, and a cathode having conducting means extending therefrom, a cavity resonator coupled between the cathode and grid conducting means and an output cavity resonator coupled between said grid and anode and having an inner conductor coupled to said anode and comprising an elongated member engaging and extending from said anode, a tubular member surrounding the elongated member but out of electrical contact therewith and completely enclosing said first tubular member, said second tubular member having an aperture therein, and electrically conducting means extending through said aperture and coupled to the interior of the output cavity resonator.

4. An electron discharge device having an envelope closed at one end by an anode forming part of the envelope for said electron discharge device, a grid within said envelope having conducting means extending radially through said envelope and a cathode within said envelope having conducting means extending through said envelope, a cavity resonator coupled between the cathode and grid conducting means and an output cavity resonator coupled between said anode and grid and comprising an inner tubular member engaging and extending from said anode, an

outer tubular member coupled to the grid conducting means and surrounding the inner tubular member but out of electrical contact therewith and completely enclosing said inner tubular member, said outer tubular member having an aperture oppositely disposed to the free end of the inner tubular member and electrically conducting means extending through said aperture and coupled to the free end of said inner tubular member.

5. A high frequency apparatus comprising a pair of concentric tubular members, the inner of said tubular members being open at its ends, said outer tubular member having apertures in the ends thereof, a pair of electron discharge devices, each electron discharge device having an anode and extending through an aperture in one end of said outer tubular member and having its anode extending within an open end of said inner tubular member and engaged thereby, each of said electron discharge devices including a grid coupled to said outer tubular member, and a cathode, and a cavity resonator coupled between the grid and cathode of each of said electron discharge devices, said outer tubular member having an aperture therein and a voltage lead extending through said aperture and contacting said inner tubular member.

6. A high frequency apparatus including a pair of oppositely disposed electron discharge devices each including an anode forming part of the envelope of the electron discharge device, said anodes being provided with longitudinally extending radiating fins and a cavity resonator coupled between said electron discharge devices and including an inner tubular member having open ends, the anode of one of said electron discharge devices being positioned within and engaged by one end of said inner tubular member and the anode of the other of said electron discharge devices being within and engaged by the other end of said inner tubular member, and an outer tubular member surrounding said electron discharge devices and said first tubular member, and a tubular member extending through but out of contact with said outer tubular member and opening into the interior of said inner tubular member for directing a cooling medium within said inner tubular member and past said radiating fins of said electron discharge devices.

7. A high frequency apparatus including a pair of oppositely disposed electron discharge devices each including an anode, a grid and cathode, said anodes forming part of the envelope for said electron discharge devices and having longitudinally extending radiating fins and a cavity resonator coupled between said electron discharge devices and including an inner tubular member having open ends, the anode of one of said electron discharge devices being positioned within and engaged by one end of said inner tubular member and the anode of the other of said electron discharge devices being within and engaged by the other end of said inner tubular member, and an outer tubular member surrounding said electron discharge devices and said first tubular member and coupled to the grids of said electron discharge devices, and a tubular member extending through but out of contact with said outer tubular member and opening into the interior of said inner tubular member for directing a cooling medium within said inner tubular member and past said radiating fins of said electron discharge devices.

8. A high frequency apparatus comprising a pair of concentric tubular members, the inner

one of said tubular members being open at its ends, the outer tubular member having apertures in the ends thereof, an electron discharge device having an anode extending through the aperture in each end of said outer tubular member and having its anode extending within an open end of said inner tubular member and engaged thereby, each of said electron discharge devices including a grid coupled to said outer tubular member and having a cathode and a resonator means coupled between the grid and cathode of each of said electron discharge devices.

9. A high frequency apparatus including a pair of oppositely disposed electron discharge devices each including an anode, a grid and cathode, said anodes forming part of the envelope for said electron discharge devices and having longitudinally extending radiating fins and a cavity resonator coupled between said electron discharge devices and including an inner tubular member having open ends, the anode of one of said electron discharge devices being positioned within and engaged by one end of said inner tubular member and the anode of the other of said electron discharge devices being within and engaged by the other end of said inner tubular member, and an outer tubular member surrounding said electron discharge devices and said first tubular member and coupled to the grids of said electron discharge devices, and cavity resonators coupled between the grids and cathodes of each of said electron discharge devices, and a tubular member extending through but out of contact with the said outer tubular member and opening into the interior of said inner tubular member for directing a cooling medium within said inner tubular member and past said radiating fins of said electron discharge devices.

10. A high frequency apparatus including a pair of oppositely disposed electron discharge devices each including an anode forming part of the envelope for said device, a grid and cathode, a radially extending grid conductor extending through the envelope and a cathode conductor extending through the envelope, said anodes being provided with longitudinally extending heat radiating fins and a cavity resonator coupled between said electron discharge devices and including an inner tubular member having open ends, the anode of one of said electron discharge devices being positioned within and engaged by one end of said inner tubular member and the anode of the other of said electron discharge devices being within and engaged by the other end of said inner tubular member, and an outer tubular member surrounding said electron discharge devices and said first tubular member and coupled to the grid conductor, and cavity resonators coupled between the grid and cathode conductors of each of said electron discharge devices.

11. A high frequency apparatus including a pair of oppositely disposed electron discharge devices each including an anode forming part of the envelope of said electron discharge device, said anode being provided with longitudinally extending radiating fins, and a cavity resonator coupled between said electron discharge devices and including an inner tubular member having open ends, the anode of one of said electron discharge devices being positioned within and engaged by one end of said inner tubular member and the anode of the other of said electron discharge devices being within and engaged by the other end of said inner tubular member, said electron discharge devices having cathodes and

5 grids within the envelopes, and an outer tubular member surrounding said electron discharge devices and said first tubular member, said outer tubular member being coupled to the grids of said electron discharge devices and a tubular member extending through but out of contact with said outer tubular member and opening into the interior of the inner tubular member for directing a cooling medium within said inner tubular member and past said radiating fins of said electron discharge devices and resonator means connected between the cathode and grid of each of said electron discharge devices.

12. An electron discharge device having an anode and a cathode, said anode forming part of the envelope of said electron discharge device, a cavity resonator coupled to said electron discharge device and including an inner tubular member having one end engaged with the anode of said electron discharge device and an outer tubular member surrounding said electron discharge device and said inner tubular member and having an aperture oppositely disposed to the free end of said inner tubular member, and a coaxial line having inner and outer conductors, the inner conductor extending through said aperture toward the free end of said inner tubular member.

13. An electron discharge device having an anode, a grid and cathode, said anode forming part of the envelope of said electron discharge device, a cavity resonator coupled to said electron discharge device and including an inner tubular member having one end engaged with the anode of said electron discharge device and an outer tubular member surrounding said electron discharge device and said inner tubular member and coupled to said grid and having an aperture oppositely disposed to the free end of said inner tubular member, and a coaxial line having inner and outer conductors, the inner conductor extending through said aperture toward the free end of said inner tubular member.

14. An electron discharge device having an anode and a cathode, said anode forming part of the envelope of the electron discharge device and having longitudinally extending heat radiating fins thereon, a cavity resonator coupled to said electron discharge device and including an inner hollow member having one end surrounding and engaged with the fins on said anode and an outer hollow member surrounding said electron discharge device and said inner hollow member, the inner hollow member opening into the interior of said outer hollow member, said outer hollow member having an aperture therein and tubular means opening into said inner hollow member for directing a cooling medium through the aperture in said outer hollow member and through said inner hollow member past said fins.

15. An electron discharge device having an anode, a grid and cathode, said anode forming part of the envelope of said electron discharge device, a cavity resonator coupled to said electron discharge device and including an inner conducting member having one end engaged with the anode of said electron discharge device and an outer tubular member surrounding said electron discharge device and said inner conducting member and coupled to said grid and having an aperture oppositely disposed to the free end of the inner conducting member, a coaxial line opening into said aperture and including outer and inner conductors, the inner conductor of said coaxial line extending through said aperture toward the

free end of said inner conducting member and resonant means coupled to said cathode and said grid, said outer tubular member having a second aperture, and a lead extending through said second aperture and contacting said inner conducting member.

16. An electron discharge device having a header member including a collar having a radially directed flange and an insulating member extending across and within said collar and sealed thereto on the inner surface only of said collar, a plurality of lead wires sealed through said insulating member, a cathode supported solely on said lead wires, a cup-shaped anode positioned over said cathode and a collar of insulating material sealed between said flange and the open end of said cup-shaped anode.

17. An electron discharge device having a header member including a collar having a radially directed flange and an insulating member extending across and within said collar and sealed thereto, a plurality of lead wires sealed through said insulating member, a cathode supported on said lead wires, an elongated tubular member having a lip sealed to said flange, a grid surrounding said cathode mounted on said elongated tubular member, a cup-shaped anode positioned over said cathode and grid and a collar of insulating material sealed between said flange and the open end of said cup-shaped anode.

18. An electron discharge device having a header member including a first collar having a radially directed flange and an insulating member extending across and within said first collar and sealed thereto, a plurality of lead wires symmetrically arranged and sealed through said insulating member, a cup-shaped cathode supported on said lead wires, an elongated tubular member having a lip sealed to said flange, a grid sur- 40

rounding said cathode and mounted on said tubular member, a cup-shaped anode positioned over said anode and grid and having a collar of U-shaped transverse section at its open end, the 5 inner lip being sealed to said anode, a second collar having a flange sealed to the flange of the first collar, and a collar of insulating material sealed between the outer lip of said U-shaped collar and the second collar.

19. An electron discharge device having a header member including a collar having a radially directed flange and an insulating member extending across and within said collar and sealed thereto, a plurality of lead wires sealed through 15 said insulating member, a cathode supported on said lead wires, an elongated tubular member having a lip sealed to said flange, a grid surrounding said cathode and mounted on said tubular member, a cup-shaped anode positioned over said anode and grid and a collar of insulating material sealed between said flange and the open end of said cup-shaped anode, said cathode and grid comprising cup-shaped members, said grid including a cap having an aperture therein and 25 means extending from the cathode through said aperture positioning said cathode relative to said grid, said means being insulated from said cap.
